UNITED STATES PATENT OFFICE.

JOHN A. CUNNINGHAM, OF SOUTH BETHLEHEM, PENNSYLVANIA.

INK-WELL.

No. 836,366.

Specification of Letters Patent.

Patented Nov. 20, 1906.

Application filed August 17, 1906. Serial No. 331,068.

To all whom it may concern:

Be it known that I, JOHN A. CUNNINGHAM, a citizen of the United States, residing at South Bethlehem, in the county of Northampton and State of Pennsylvania, have invented a new and useful Ink-Well, of which the following is a specification.

This invention relates to ink-wells; and its object is to provide means for limiting the movement of a pen while being inserted into the well, so as to prevent too large an area of the pen and its holder from coming into contact with the ink, said means being also capable for use as a closure for the ink-well.

15 A still further object is to provide an ink-well which is so shaped interiorly as to permit the stop device to assume a position therein where it will not interfere with the use of all of the ink contained within the well.

20 A still further object is to provide a stop which is of novel construction, which can be readily manipulated, and which will not injure the point of the pen contacting therewith.

With the above and other objects in view 25 the invention consists of an ink-well having a recess in the bottom thereof in which a stop device of peculiar construction is adapted to be seated. This stop device consists of a slotted base having a top covering of rubber 30 or other material which is detachably fastened in the slot. A threaded stem projects from the base of the stop and is slidably mounted within a cover adapted to be placed on the well. Means are provided whereby 35 this stem cannot rotate within the cover, but said stem and the stop device connected to it are adjustable vertically by means of a device provided for that purpose. An opening for the reception of pens is formed in the cover 40 and by adjusting the stop device the stem can be brought into position to close said opening.

The invention also consists of certain other 45 novel features of construction and combinations of parts, which will be hereinafter more fully described and pointed out in the claims.

In the accompanying drawings is shown the preferred form of the invention.

In said drawings, Figure 1 is a vertical section through the ink-well and showing by dotted lines the position which the stop may assume in the bottom recess. Fig. 2 is a plan view of the well with the cover removed. Fig. 3 is a plan view of the cover. Fig. 4 is a 55 detail view of the stop and its stem. Fig. 5 is a bottom view of the stop. Fig. 6 is a vertical

section through a modified form of ink-well. Fig. 7 is a horizontal section through the up-standing flange of the ink-well shown in Fig. 6, and Fig. 8 is a bottom plan view of the stop. 60

Referring to the figures by characters of reference, 1 is a well having a concave bottom 2 provided at the center with a recess 3 for the purpose hereinafter set forth.

A circular flange 4 is disposed around the upper or open end of the well and constitutes a seat for a cover 5. An opening 6 is formed within the cover, and a screw-threaded stem 7 is slidably mounted within this opening and extends upward from the base 8 of a stop 9. This base is shaped to fit snugly within the recess 3 and has a slot 10 extending into one side thereof, said slot being contracted at a point between its ends, as shown at 11. This slot is adapted to receive and 75 retain a headed lug 12, extending downward from a protecting-strip 13, formed of rubber or other suitable material and which conforms in outline with the base 8 and rests flat thereon. The lug 12 is formed of the same 80 material as the strip 13 and is adapted to be compressed when forced through the contracted portion of the slot and subsequently expand, so as to retain the strip in proper position. The stem 7 is adapted to clamp one 85 end portion of the strip 13 upon the base.

A groove 14 extends longitudinally of the stem, and a lug 15 is formed within the opening 6 and projects into this groove, so as to prevent the stem from rotating. A thumb-nut 16 is mounted on the stem and normally rests on the cover 5, and by rotating this stem the stop 9 can be either raised or lowered. An opening 17 is formed within the cover directly above a portion of the stop 9 and is 95 of sufficient size to receive a pen. When the stop is raised against the cover by rotating the nut 16, the same can be brought into position to close the opening 17 and prevent evaporation of the ink or the admission of 100 dust, &c., thereto. The normal position of the stop 9 is against the cover 5 and closing the opening 17.

When it is desired to use the ink-well, the nut 16 is rotated so as to permit the stop to 105 lower a predetermined distance below the surface of the ink within the well. A pen can then be inserted through the opening 17 until the point thereof contacts with the strip 13. As the supply of ink becomes less 110 the stop can be still farther lowered into the well, and this operation can be continued un-

til said stop becomes seated within the recess 3. When it assumes this position, it will force from said recess any ink which may have accumulated therein, and said ink will 5 assume a position above the stop, where it can be easily contacted by the pen-point.

When the well is not in use, the nut 16 is turned so as to draw the stop into position to close the opening 17.

10 It is to be understood that the well may be made of any desired size and proportions, and if the same is formed with glass the ink contained within it may be concealed by silvering the interior of the well or by surrounding the ink-holding recess with a non-transparent portion containing suitable insignia, initials, &c.

It will be noticed that the cover 5 has a depending flange 18 upon its lower face and 20 around the openings 6 and 17, and this flange constitutes a seat for the strip 13 when the cover is closed thereby.

Instead of constructing the ink-well in the manner shown in Figs. 1 and 2, wherein a removable cover is employed, the ink-well can be of the construction illustrated in Figs. 6 and 7, wherein the body 19 is frusto-conical and has an integral cover 19^a, in which is formed an inlet-opening 20, surrounded by 25 an upstanding flange 21. An opening 22 extends downward through the flange and communicates with the opening 20, and slidably mounted in this opening is a stem 23, having its upper portion screw-threaded, as at 24, 30 while its lower portion engages the base 25 of a stop. This stop has an upper covering 26, formed of a strip of rubber or other flexible material, which extends beyond the edges of the base 25. Said base is of such size as to be 35 readily inserted through the opening 20 and the passage 22, although to insert it it would be necessary for the strip 26 to fold upward.

A groove 27 is formed longitudinally within the stem and is adapted to be engaged by a 40 lug 28, extending at right angles from a stem 29, upstanding from flange 21. A hollow nut 30 engages the threaded portion of the stem and bears upon the flange 21, stem 29 and lug 28 being normally positioned within 45 the nut. The distance between the nut and the front portion of the flange 21 is sufficiently large to permit the insertion of a pen, and as the quantity of ink decreases the nut 30 can be rotated so as to permit the stop 25 50 to move farther into the well. When it is desired to close the well, the stop is moved upward until the strip 26 contacts with the upper end of the well, as shown in Fig. 6, whereupon the well will be tightly sealed.

55 The preferred form of the invention has been set forth in the foregoing description; but I do not limit myself thereto, as I am aware that modifications may be made there-

in without departing from the spirit or sacrificing the advantages thereof, and I therefore reserve the right to make such changes as fairly fall within the scope of the claims. 65

What is claimed is—

1. The combination with a well and an apertured cover therefor; of a stop adjustably 70 connected to the cover and projecting into the well, said stop constituting a closure for the aperture.

2. The combination with a well; of an apertured cover, a stop, a stem projecting from 75 the stop and through the cover, and means upon the stem for adjusting the stop within the well, said stop adapted to constitute a closure for the aperture.

3. The combination with a well; of a cover 80 having a pen-receiving aperture therein, a combined aperture-closure and pen-stop adjustably connected to the cover, and a flexible cover upon said stop.

4. The combination with a well; of a cover 85 having an aperture therein, a stop, a stem upon the stop and extending through the cover, means for adjusting the stem longitudinally to move the stop into position to close the aperture or into position therebelow, and a flexible cover upon the stop.

5. The combination with a well having a recess in the bottom thereof; of a cover having an aperture, a stop adapted to be seated within and above the recess, and means for 95 adjusting said stop from or toward the cover, said stop adapted to constitute a closure for the aperture.

6. The combination with a well having a recess in the bottom thereof; of a stop adapted to be seated within or supported above the recess, an apertured cover, a threaded stem extending from the stop and through the cover, and means upon the stem for adjusting the stem longitudinally within the cover, said 100 stop adapted to contact with the cover and close the aperture.

7. The combination with a well having a recess in the bottom thereof; of a cover having apertures therein, and an integral depending flange surrounding the apertures, a stem adjustably mounted within one of the apertures, means for adjusting the stem longitudinally, and a stop at one end of the stem and adapted to be seated within or above the 110 recess, said stop comprising a slotted base, a flexible strip, and means within the slot for securing the strip to the base.

In testimony that I claim the foregoing as my own I have hereto affixed my signature in 115 the presence of two witnesses.

JOHN A. CUNNINGHAM.
